UNITED STATES PATENT OFFICE.

WILLIAM BENJAMIN WRIGHT, OF BOSTON, MASSACHUSETTS.

PAPER-CARRYING ATTACHMENT FOR TYPE-WRITING MACHINES.

SPECIFICATION forming part of Letters Patent No. 448,288, dated March 17, 1891.

Application filed March 8, 1890. Serial No. 343,203. (No model.)

To all whom it may concern:

Be it known that I, WILLIAM BENJAMIN WRIGHT, of Boston, in the county of Suffolk and State of Massachusetts, have invented 5 a new and useful Improvement in Type-Writers, of which the following is a specification, reference being had to the accompanying drawings, in which—

Figure 1 is a rear elevation of so much of 10 one form of type-writer embodying my invention as is necessary for an understanding of my improvement. Fig. 2 is an end elevation, and Fig. 3 a plan, of what is shown in Fig. 1, the roll of paper being removed in Fig. 3 for 15 greater clearness. Fig. 4 is an end view of my new roll.

The object of my invention is to produce a type-writer which prints from a roll of paper or the like; and the main feature of my invention 20 is a type-writer having the herein-after-described paper-carriage provided with a roll of paper to be printed.

In the drawings my invention is shown embodied in the well-known Remington type-writer, only so much of that machine being 25 shown, however, as is necessary for an understanding of the nature of my invention, A being the base, a the rear uprights, a' the rod on which the frame of the feeding device 30 and the support a², carrying the spacing-rack, slide, and 1 being the stop carried by the adjustable screw 2 to regulate the length of line printed. The screw 2 slides in a slot 3 in the 35 bracket a². The rack carried by the bracket a² is represented by 4.

My paper-carriage B, supporting the roll b of strips to be printed is in this embodiment of my invention connected to the support a² by arms b' b', and supported on a track B' 40 conveniently formed on bracket B² secured to frame of the machine. As shown, the carriage is provided with grooved wheels b², two on one edge of track B' and one on the other edge. This is a convenient way of keeping the carriage on its track. The supports b³, in which the journals b⁴ of roll b rest, are constructed 45 so that the roll may be removed when the paper is exhausted and a fresh roll put in its place. It is desirable to provide a tension b⁵

to prevent the roll b from unwinding too rapidly. Carriage B may be of any suitable shape and construction, but is preferably a casting shaped as shown in the drawings—that is, a casting with two uprights forming the supports b³ for the roll b, and with a downward projection b⁶, carrying a grooved wheel b², which works on that edge of track B' which is farthest from the roll, and steadies the carriage and helps keep it on the track, the carriage being provided with other grooved 55 wheels b², which run on the upper edge of the track B'. Two arms b' b' are preferably employed, and are loosely pivoted to carriage B and connected to rack-support a², say, by a screw 5, the arms b' b' being connected in this 60 case by a cross-bar 6. The upper ends of the supports b³ are best formed with open slots 7, in which the journals b⁴ of roll b rest, to allow 65 rolls of paper to be readily put in and taken out. The bracket B² is conveniently formed 70 of casting having a web 8, one edge of which fits under the flange 10 of the frame of the machine, while the other edge 11 rests on base or frame A of the machine. It will be obvious to all skilled in the art that the construction shown must be varied to adapt my invention to different forms of type-writers, and that the form and construction of the parts herein set forth may be changed without departing from my invention. When the support a² is slid along on the rod a', the paper-carriage B is moved, carrying the roll of paper 75 endwise, and the paper is thereby brought into proper relation with the type, as will be plain without further description.

It will be plain to all skilled in the art that the carriage and its track may be greatly changed in form, if desired, and the track may be an integral part of some portion of a machine embodying my invention. In Fig. 2 80 only a single strip of paper is shown on roll b, but in Fig. 4 the roll is provided with alternate strips of printing-paper x and transfer-paper y. In preparing these rolls for the market I ordinarily perforate the strips x at 85 different distances to provide sheets of standard sizes.

What I claim is—

1. In a type-writer, a rack-support, a paper-carriage, a track therefor, and means—for example, one or more arms from the carriage—for connecting the carriage and rack-support, combined and operating substantially as and for the purpose set forth.
2. The herein-described type-writer attach-

ment, consisting of bracket B², track B', paper-carriage B, and one or more arms b', substantially as and for the purpose set forth.

WILLIAM BENJAMIN WRIGHT.
